FIG. 1 is a top plan view of a unitary manifold embodying my improved ornamental design;

FIG. 2 is an end elevation of the same;

FIG. 3 is an elevation view of the opposite end of the manifold; and

FIG. 4 is a cross section taken on the line 4—4 of FIG. 1.

A side elevation view of the manifold, a bottom plan view and an opposite side elevation are all similar to the top plan view shown in FIG. 3, and hence are thought unnecessary in the drawings.

I claim:

The ornamental design for a unitary manifold for water filtration systems, essentially as shown and described.
